Primary Examiner—Terry A Wallace(74) *Attorney, Agent, or Firm*—Taylor & Aust, P.C.(57) **CLAIM**

The ornamental design for a utensil, as shown and described.

DESCRIPTION

FIG. 1 is an isometric view of a utensil showing my new design, the broken lines are for illustrative purposes only and form no part of the claimed design.

FIG. 2 is a top plan view thereof; and,

FIG. 3 is a side view thereof.
